UNDERFEED STOKER, INCLUDING PROGRESSIVE OVERFEED GRATES

George P. Jackson, Flushing, N. Y., assignor, by mesne assignments, to Combustion Engineering-Superheater, Inc., a corporation of Delaware

Application November 27, 1946, Serial No. 712,479

2 Claims. (Cl. 110—47)

1

This invention relates to stokers and particularly to overfeed grates associated with retort stokers.

It is an object of this invention to provide an improved overfeed grate which will effectively break up the fuel bed thereon while advancing the fuel thereacross.

Other objects and advantages will become apparent as the description hereof proceeds.

One illustrative form of the invention is shown by the accompanying drawings wherein:

Figure 1 is a longitudinal section taken on line 1—1 of Figure 2 through a single retort stoker embodying the improved grate;

Figure 2 is a transverse section taken on line 15 2—2 of Figure 1; and

Figure 3 is a partial half section, similar to Figure 2, showing a modification of the improved grate shown in Figure 2.

In the preferred embodiment of the invention a series of grate members have their individual motions so inter-related that they produce an advancing movement of the fuel along the grate and a breaking-up action of the fuel bed. This action is particularly advantageous when burning coking or caking coals.

Referring to Figure 1, beneath the usual fuel hopper 10 at the front end of the stoker is a fixed plate 11 over which a pusher 12 reciprocates and pushes the fuel from the hopper through the throat 13 and thence into and through the retort 14. The retort 14 extends from the throat 13 to the rear of the stoker. A sliding bottom plate 15 at the bottom of the retort 14 rides upon fixed plate 11 and is reciprocated by a rod 16 fastened to plate 15 by a lug 17 which extends downwardly through a slot 18 in fixed plate 11. Rod 16 extends forwardly through the stoker front 19 and is fastened to a cross head 20. Cross head 20 also is fastened to the pusher 12 by rod 21 and to the piston rod 22 which is fastened to the piston 23 within the cylinder 24.

As the piston is operated by a fluid under pressure to reciprocate, it reciprocates the pusher 12 and the sliding bottom plate 15. Mounted on the sliding bottom plate 15 is a wedge 25 which aids in advancing and distributing the fuel through the retort 14. There may be several such wedges 25 mounted longitudinally along the sliding bottom plate 15 depending upon the desired distribution of the fuel within the retort. The fuel advances through the retort 14 in a rearward and upward direction, over-flowing transversely onto the grates 26 located on either side of the retort.

2

The grates are preferably symmetrically similar on both sides of the retort 14 and comprise a multiplicity of parallel rows of transversely aligned separate bars whose upper fuel-supporting surfaces slope generally downwardly from the retort 14 toward the furnace side walls 27. As shown in Figure 2, there are two such aligned bars in each row, a top bar 28 and a lower bar 29. Each of the upper bars 28 in the two side rows shown is supported at its inner end by the top side of retort 14 which on each side of the retort is formed into a longitudinally extending shaft 30 upon which the bearings 31 of bars 28 turn.

The outer ends of bars 28 rest upon the upper top surfaces of the lower bars 29. Lower bars 29 are supported at their inner ends by a longitudinally extending shaft 32 upon which the bearings 33 of bars 29 turn. The outer ends of bars 29 rest upon the top of outer plates 34 which are fastened to a stoker frame member 35. The shaft 32 is connected by a number of arms 36 to a shaft 37, so that when the latter turns about its axis back and forth through a limited arc, the shaft 32 will oscillate through a limited arc and raises and lowers the inner end of bar 29 through said arc. The outer end of the upper bar 28 which rests upon the lower bar 29 is in turn rotated up and down about its bearing 31. An ash dump gate 38 of the usual type extends from the plate 34 to the wall 27 and is fastened to a rocker shaft 39 which in turn is mounted to the stoker frame 35.

The shafts 37, one located at each side of retort 14 extend from the bearings 40 (see Figure 1) attached to the rear stoker frame 41 forwardly through the bearings 42 attached to the front stoker frame 43. On the forward end of each shaft is mounted a bevel gear 44 which meshes with a bevel gear 45 mounted on a lever 46 which is caused to oscillate through an arc about the axis of bevel gear 45. Bearing means 47 support the gear 45 and the lever from the bottom side of hopper 10.

The lower portion of lever 46 is provided with a longitudinal slot 48 within which slides a nut 49. A long-threaded bolt 50 extends longitudinally of the slot, engages the nut 49 and is mounted within the lever 46 so as to prevent any longitudinal movement with respect thereto. By turning bolt 50, the nut 49 may be moved radially along the slot 48 of the lever so as to increase or decrease the radial distance of the nut 49 from the bearing means 47.

Attached to nut 49 is pin 51 which supports

one end of a connecting rod 52, the other end of the rod being supported by pin 53 which is fastened to cross head 20. As the cross head 20 reciprocates, the connecting rod 52 oscillates the lever 46 which, by means of bevel gears 45 and 44, causes shaft 37 to turn back and forth through an arc and thereby raises and lowers the inner ends of bars 29. By increasing or decreasing the radial distance of nut 49 from bearing means 47, the movement of bar 29 may be proportionately decreased or increased.

In Figure 3 each row of transversely aligned bars comprises three members, an upper bar 28', an intermediate bar 70 and a lower bar 29'. Like the upper bar in Figure 2, upper bar 28' is constructed to hinge at its inner end, on the top tuyère side of shaft 30' in bearing 31' and to rest upon the intermediate bar 70 at its outer end. The intermediate bar 70 is constructed to hinge at its inner end on the shaft 32' and to rest upon the lower bar 29' at its outer end. Shaft 32' is connected to rocker shaft 37' by arms 36'.

The lower bar 29' of Figure 3, like the lower bar in Figure 2, is constructed to hinge at its inner end (via bearing 33') on a shaft 71 and to rest upon the outer plate 34' at its outer end. The rocker shaft 37' is the equivalent of the rocker shaft 37 in Figure 2 and is turned back and forth through an arc by means the same as those used for driving shaft 37, and thereby raises and lowers the shaft 32' and the inner end of bar 70. The rocker shaft 72 is connected to shaft 71 by arms 76. Rocker shaft 72 is similar to rocker shafts 37, 37' and extends from the front to the rear of the stoker and is supported by bearings in the front and rear stoker frames in the same manner as is shaft 37.

Rocker shafts 37' and 72 are interconnected as by a connecting rod 73 and crank arms 74 and 75 (shown diagrammatically in Figure 3), so that as shaft 37' turns back and forth through an arc, shaft 72 is caused to turn through a similar arc and thereby lowers and raises the shaft 71 and the inner end of bar 29'. Rod 73 may be made adjustable in length by well known means so that the movement of rocker shaft 72 may be varied with respect to that of rocker shaft 37' and thereby the movement of bar 29' with respect to that of bar 70.

In both Figures 2 and 3 the movements of bars 29, 70 and 29' may be varied by rotating the respective arms 36, 36' and 76 with respect to rocker shafts 37, 37' and 72 from the positions shown in the figures. For example, by rotating the arms counter-clockwise, a relatively smaller lift will be given the associated bars but a relatively greater horizontal movement.

In operation of the thus-improved stoker, fuel is fed from the hopper 10 and delivered by the pusher 12 into the retort on tuyère 14 whence it overflows transversely onto the grates. The movement of the grate bars together with the downward slope of the grates causes the fuel to advance toward the ash dump grates 38 while it is burning. Air for combustion is forced upwardly from duct 51 (see Figure 2) into windbox 58 and thence to boxes 59 and 60 through openings 61 and 62. The amounts of air to the boxes 61 and 62 are controlled by sliding dampers 63 and 64 in the openings 61 and 62.

The relative extreme movements of the grate bars 28 and 29 in Figure 2 are shown by the full and dashed lines. The bars in their uppermost position are retracted toward the retort with re-

spect to the direction of fuel movement and when moving downwardly push the fuel toward the dump grate. The upward movement of both the upper bars 28 and lower bars 29 where they contact, lifts the fuel bed and breaks it thereabove thereby breaking any coke masses that may have formed there. The movement of the inner end of the upper bar 28 adjacent the retort is in a horizontal direction which aids in breaking up any coke formation that may have been formed at the top sides of the retort.

The relative movements of grate bars 28' and 70 of Figure 3 are similar to bars 28 and 29 described above for Figure 2 and function to break possible coke masses at the same locations. There are, however, further advantages relative to movements between the bars of Fig. 3. As, for example, the shaft 37 turns clockwise and lowers the inner end of intermediate bars 70, the shaft 72 turns counter clockwise and raises the outer end of said bar and consequently the bar 70 will tilt through a greater angle than the remaining links. Furthermore a second lifting action of the fuel occurs at the juncture of intermediate bar 70 and the lowermost bar 29'. By these combined motions the fuel bed is subjected to a greater breaking action than occurs with the bars of Figure 2.

Obviously different relative motions may be obtained between rocker shafts 37' and 72 in Figure 3 by varying the relative angular positions of arms 74 and 75 on their respective rocker shafts. In this manner different relative motions may be imparted to bars of the grate.

From the above disclosure, it may be seen that the relative movements of the links provide movements within the fuel bed which aid in pushing the fuel down the grate and in breaking up objectionable coke formations within the bed. Tests made on the improved stoker grate have shown substantial improvement in combustion rates for certain fuels when compared to similar stokers having moving grates but not equipped with the improved grates. It may also be seen that the bars may be easily removed by lifting them off their supports from above without disturbing any other part of the stoker.

While the preferred embodiment of my invention has been shown and described, it will be understood that minor changes in construction, combination and arrangement of parts may be made without departing from the spirit and scope of the invention as claimed.

What I claim is:

1. In a stoker, a retort extending longitudinally of the stoker, an overfeed grate comprising a multiplicity of parallel rows of bars extending transversely outwardly from one side of said retort and including at least three bars per row, the bars in a row being aligned with the outer end of one bar overlying the inner end of an adjacent bar; means for moving fuel from said retort onto said grate; a pivotal bearing at the underside portion of each of the bars and at the inner end of each of the bars in a row, the bearings of the bars of each row being aligned longitudinally with the bearings of the longitudinally adjacent bars; all of the bars in said rows, excepting the outermost bars, being freely supported at their outer ends on the upper surfaces of the inner ends of the next adjacent outer bars; a plate freely supporting the outer ends of the outermost bars; means on said retort side supporting the pivotal bearings of all of said innermost bars; shafts extending longitudinally of the

stoker and supporting the aligned pivotal bearings of all of said remaining bars; a rocker shaft for each of said bearing shafts spaced therefrom and parallel thereto, and arms connecting the rocker and bearing shafts; means for turning said rocker shafts back and forth through a predetermined angle including means for oscillating said rocker shafts in opposite directions to each other to thereby move the pivoted ends of the associated bars through oppositely rotating predetermined vertically inclined arcs whereby to cause the relative movement of adjacent transversely aligned bars to agitate the fuel bed thereabove and to assist its advance along the grate.

2. In a stoker, a retort extending longitudinally of the stoker, an overfeed grate comprising a multiplicity of parallel rows of bars extending transversely outwardly from opposite sides of said retort and including at least three bars per row, the bars in a row being aligned with the outer end of one bar overlying the inner end of an adjacent bar; means for moving fuel from said retort onto said grate; a pivotal bearing at the underside portion of each of the bars and at the inner end of each of the bars in a row, the bearings of the bars of each row being aligned longitudinally with the bearings of the longitudinally adjacent bars; all of the bars in said rows excepting the outermost bars, being freely supported at their outer ends on the upper surfaces of the inner ends of the next adjacent outer bars; a plate freely supporting the outer ends of the outermost bars; means on said retort sides supporting the pivotal bearings of all of said innermost bars; shafts extending longitudinally of the stoker and supporting the aligned pivotal bearings of all of said remaining bars; a rocker shaft

for each of said bearing shafts spaced therefrom and parallel thereto, and arms connecting the rocker and bearing shafts; means for turning one of said rocker shafts back and forth through a predetermined angle; crank arms on said one rocker shaft and an adjacent rocker shaft; and adjustable connecting rods between said crank arms arranged to drive and reverse the direction of angular movement of said adjacent rocker shaft with respect to said one rocker shaft and to vary the angular locations of their respective arcs of rotation with respect to the associated bars, to thereby move the pivoted ends of the associated bars through oppositely rotating arcs having optionally different horizontal and vertical component movements whereby to cause the relative movements of adjacent transversely aligned bars to agitate the fuel bed thereabove and to assist its advance along the grate.

GEORGE P. JACKSON.
